UNITED STATES PATENT OFFICE.

HORACE G. ALEXANDER, OF SOUTH LONDONDERRY, VERMONT.

PICKER CYLINDER FOR RAG-PICKING MACHINERY.

Application filed May 31, 1924. Serial No. 716,945.

To all whom it may concern:

Be it known that I, HORACE G. ALEXANDER, a citizen of the United States, residing at South Londonderry, in the county of 5 Windham and State of Vermont, have invented a new and useful Picker Cylinder for Rag-Picking Machinery, of which the following is a specification.

This invention relates to a picker cylinder 10 for use in the shredding of waste rags and other woven fabrics to produce shoddy. As ordinarily made, these machines are made with cylinders provided with teeth which tear the rags apart and separate the fibers 15 from them so that they can be used over again. These cylinders usually are of wood and the teeth which are used for the purpose of shredding the rags are formed by nails or spikes driven through the cylinder. They 20 get loose eventually and when they do, the holes in which they are placed are so enlarged that it is practically impossible to put them back. This involves considerable waste. Furthermore, the number that can 25 be placed on the cylinder is limited.

The principal object of this invention is to provide a metal cylinder having a much longer life than the wooden cylinder and to provide means for mounting therein metal 30 teeth which will stay in position and therefore outlast many times the nails and other points that are ordinarily employed.

Other objects and advantages of the invention will appear hereinafter.

Reference is to be had to the accompanying drawings, in which—

Fig. 1 is a side view, with the frame or casing in section, of a rag picking machine constructed in accordance with this invention;

Fig. 2 is a side view of the cylinder partly in section on enlarged scale;

Fig. 3 is a radial sectional view of the cylinder;

Fig. 4 is a perspective view of one of the strips of teeth; and

Fig. 5 is a perspective view of the fastening means therefor.

I have shown the invention as applied to 50 an ordinary type of rag picking machine comprising a frame 10, a feeding table 11, feed rolls 12 and retaining plate 13. Properly driven by power is a shaft 14 carrying a cylinder 15 which rotates adjacent to the 55 retaining plate. This cylinder in accordance with this invention is formed of metal

and provided with a series of longitudinal grooves 16 having perforations 17 behind them for receiving fastening bolts 18. At the sides, these grooves 16 are offset at 19 to form undercut recesses. In each of these grooves I place two sheet metal plates 20 each having integral teeth 21 of a general triangular shape. These plates are provided with a ledge 22 on one side. 60 65

In setting the parts up, two of these plates are placed in each of the grooves 16 at its opposite sides with their ledges 22 projecting in opposite directions and fitting into the undercut recesses 19. The two plates, like 70 the groove 16, extend throughout the length of the cylinder and the teeth on the two plates in the same groove are staggered with respect to each other. The teeth of the two adjacent plates of consecutive grooves are 75 also staggered. Between the two plates I force a wedge-shaped retaining piece 24 and put one or more bolts 18 through this extending to the inside of the cylinder and fasten them with nuts inside. This fastens 80 the two plates in the groove permanently although they can be detached for repairs and replacement. The ledges 22 fitting in the undercut recesses 19 prevent the plates from drawing out radially while the clamping piece 24 prevents their moving longitudinally or laterally. This forms a firm 85 clamping means and secures the plates permanently in position although they can be taken out to replace them if they get broken 90 or worn.

The particular construction of the cylinder may vary within wide limits. I have shown two spiders 26 at the ends fixed to the shaft 14 and shown here as bolted inside 95 by bolts 27 to the cylinder 15. On the end I have shown end plates 28 having flanges 29 projecting inwardly over the edges of the cylinder. This constitutes a firm and mechanical way of mounting the heavy cylinder and securing the teeth thereto. 100

It will be seen that the teeth are of triangular shape and project from the cylinder radially so that they will shred the fabric properly and will not be bent unduly or if they are bent, it does not make them project any farther from the cylinder and consequently does not result in the striking of the metal teeth against the metal retaining plate 13. That has been a fault which has 110 been present in some cases and it is a very serious one because the striking of the metal

parts together causes sparks and results in fire. This is prevented here because any distortion of the teeth will make them project less than the normal distance from the surface of the cylinder. They project to their maximum distance when they are new and are mounted in proper position.

On account of this construction I can provide the cylinder with many more teeth of the same fineness than is the case at present. This improves the efficiency of the machine.

Although I have illustrated and described only a single form of the invention I am aware of the fact that modifications can be made therein by any person skilled in the art without departing from the scope of the invention as expressed in the claims. Therefore I do not wish to be limited to all the details of construction herein shown and described but what I do claim is:—

1. In a rag picking machine, the combination with means for feeding and holding the rags, of a metal cylinder having numerous metal strips located longitudinally and having integral teeth arranged in parallel relations thereon and extending therefrom radially for engaging the rags and shredding them.

2. In a machine of the character described, the combination with means for feeding and presenting the rags, of a metal cylinder located adjacent thereto and provided with numerous double rows of metal teeth projecting radially from the surface of the cylinder, the teeth being formed in strips, and

means extending through the wall of the cylinder for holding the strips within the surface of the cylinder and projecting therefrom.

3. A cylinder for a machine of the character described consisting of metal and having a series of longitudinal parallel grooves along its surface, each having undercut recesses in its opposite sides, each groove being provided with two strips of metal each having an outward flange fitting in one of said recesses, and means within the grooves for holding them apart against the side walls of the grooves.

4. As an article of manufacture, a cylinder for the purpose described having a series of parallel grooves arranged on its surface, each groove having two undercut opposite recesses extending along it, a series of strips of metal, each having a flange at the edge and provided with a series of teeth at the opposite edge, said strips of metal being set into the grooves at opposite sides thereof with the flanges turned outwardly so as to project into said undercut recesses, and fastening means located between the two strips in each groove for holding the strips outwardly against the walls of the grooves with their flanges in the recesses, and means extending through the wall of the cylinder for detachably holding said fastening devices in position.

In testimony whereof I have hereunto affixed my signature.

HORACE G. ALEXANDER.
